We claim the ornamental design for a four-leafed vehicle electrical center subassembly, as shown and described.

DESCRIPTION

FIG. 1 is a perspective view of a four-leafed vehicle electrical center subassembly, showing our new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom view thereof showing an unclaimed alternate bottom usage environment.

The broken line portions shown in each of the figure drawings is included to show unclaimed subject matter only and forms no part of the claimed design.
